Benjamin Podolsky,
By his Attorney, Leo. F. Healy

UNITED STATES PATENT OFFICE.

BENJAMIN PODOLSKY, OF NEW YORK, N. Y.

DESIGN FOR A CAP.

59,512.

Specification for Design.

Patented Oct. 25, 1921.

Application filed June 2, 1921. Serial No. 474,581. Term of patent 3½ years.

To all whom it may concern:

Be it known that I, BENJAMIN PODOLSKY, a citizen of the United States, residing at the borough of Manhattan, city, county, and State of New York, have invented a new, original, and ornamental Design for Caps, of which the following is a specification, reference being had to the accompanying drawing, forming part thereof.

Fig. 2, is a perspective view of a cap, showing my new design.

I claim:

The ornamental design for a cap, as shown.

BENJAMIN PODOLSKY.
